Application July 19, 1933, Serial No. 681,104

3 Claims. (Cl. 250—35)

Our invention relates to X-ray generators having a hot cathode, and more particularly to such tubes having a control element therein whereby the direction and amount of the cathode ray stream between anode and cathode may be changed at will independently of the cathode or anode supply. The invention further relates to methods of generating X-rays having peculiar characteristics, this application being a continuation in part of our prior application, Serial No. 580,836, filed December 14, 1931.

Among the objects of our invention are: To provide an X-ray tube wherein the electron stream can be controlled independently of the anode and cathode supply; to provide an X-ray tube in which a space charge is present during a substantial part of the time that X-rays are being generated; to provide an X-ray tube which may be made self-oscillating at high frequencies; to provide an X-ray tube in which the size of the focal spot may be changed electrically; to provide an X-ray tube in which the position of the focal spot may be changed electrically; to provide an X-ray tube in which the envelope is effectively protected from secondary electron bombardment; to provide an X-ray tube in which stray X-radiation outside the main beam is reduced to a minimum; to provide an X-ray tube of increased efficiency; to provide an X-ray tube of simple construction and in which the elements are in concentric relation; to provide an X-ray tube having a minimum band of X-ray wavelengths in the active beam; and to provide a greatly improved X-ray generator and novel methods of operation.

Other objects of our invention will be apparent or will be specifically pointed out in the description forming a part of this specification, but we do not limit ourselves to the embodiment of our invention herein described, as various forms may be adopted within the scope of the claims.

Referring to the drawings, which illustrate several embodiments of our invention:

Figure 1 is a view in elevation of the elements of a right angle X-ray tube embodying our invention, the envelope being cut away and shown in section.

Figure 2 is an enlarged plan view of the cathode and control electrode, the cover of the control electrode being removed.

Figure 3 is an enlarged view partly in section and partly in elevation showing the relations of anode, cathode and control electrode.

Figure 4 is a sectional view of another embodiment of our invention.

Figure 5 is a schematic diagram of a circuit in which the tube may be used.

Figure 6 is a schematic diagram of another embodiment of our invention as used to control the position of the focal spot.

Figure 7 is a schematic diagram of the tube of our invention as used in an oscillating circuit.

Our invention, broadly considered from the point of view of apparatus, comprises an X-ray tube containing an annular cathode, and an anode, preferably of conical shape positioned in the axis of the circle described by the cathode, the apex of the anode cone being usually placed in substantially the center of the circle. The cathode is enclosed by a control electrode having preferably a concentric annular aperture between the cathode and anode. The control electrode is adapted to be separately energized to give control of the electron flow to the anode. It may also be desirable to make use of the control thus afforded to cause the X-ray tube to be self-oscillatory at high frequencies by the use of proper exterior circuits, thus giving rise to an X-ray beam pulsating at high frequencies.

Considered broadly as to methods involved, we are able to control the cathode ray current and consequently the intensity of the X-ray beam by changing the thickness of the cathode ray stream. We also utilize the method of changing the thickness of a discoidal cathode ray stream to change the size of the focal or impact spot, and we also change the direction of the discoidal stream to change the position of the focal spot. We may desire to make the X-ray beam pulsate at high frequencies by making the cathode ray current self-oscillatory, thereby producing an X-ray having peculiar results of unexpected character.

In the detailed description of the preferred forms of our invention which follows, wherein certain relative dimensions are shown and described, and certain specific circuits are mentioned, it is to be understood that these dimensions are relative only and may be departed from widely in order to adapt the apparatus to various kinds of radiographic, therapeutic, diagnostic or experimental uses, and that other equivalent circuits may be substituted for the specific ones disclosed, without departing from the spirit of this invention.

It is also to be understood that we do not at this time, desire to offer any extended explanation or discussion of the theories involved in this invention.

application, nor be bound by such explanation as may be herein necessary, as the state of the X-ray art is such that the final satisfactory theories can only be arrived at by constant and continued experimentation, and coordination and assembly of widespread observations. In such a rapidly advancing field, additional data might well modify or completely change presently held theories, without, however, necessitating change or modification of apparatus or method beyond the scope of the appended claims.

In the drawings, referring especially to Figures 1, 2, and 3, an envelope 11 is provided with an anode arm 12 and a shorter cathode arm 13. It is preferred that the arms be placed at right angles, leaving a radiation window 14 free of obstructions.

A cathode stem 15 is sealed in the end of the cathode arm and supports a control electrode assembly 16 by means of control rods 17 fastened to a band 19 clamped to the stem by bolts 20.

The control electrode assembly comprises a hollow cup-shaped body which has a cover 21, a circumferential side wall 22 and a face plate 24, the latter being provided with a cone shaped radiation aperture 25 positioned to face the radiation window 14. The cover 21, which may be removed by taking out screws 26, and the inner surface of the face plate are preferably dished sufficiently to form an annular aperture 27 somewhat narrower in width than the interior chamber width next the side wall. The cover is provided with a central anode aperture 28.

Cathode supports 29 are sealed to and thereby positioned parallel to the control rods 17 by a spacer 30 preferably formed from quartz. These leads project into the control electrode chamber through cathode support apertures 31.

An annular cathode 32 preferably formed from a tantalum or tungsten coil is fastened to the leads concentric with the side wall 22 about midway between the side wall and the annular aperture 27. Quartz or like insulators 34, set around the side wall carry hooks 35 by which the cathode is maintained in its concentric position.

Cathode leads 36 and a control lead 37 are sealed through a pinch 39 of the cathode stem 15, and connect with the cathode supports and a control rod, respectively.

In the anode arm, a long anode rod 40, preferably of heavy copper is provided with a welded skirt 41 of a material which will seal to the envelope material to form a ring seal 42, with a reentrant tube 44.

The anode rod continues on in the central axis of the tube and terminates in an anode plug 45 preferably of tungsten set into and fastened to the end of the rod, and exposing a coned target surface 46.

The tip of the target cone projects through the anode aperture 28 in the control electrode cover by an amount which may be varied, as will be later described, but in any event, it is preferable that the tip of the cone be in the axis of the circle described by the annular cathode. It is also desirable to make the total diameter of the anode rod somewhat larger than the cover aperture so that the shoulders of the anode rod will shield the anode end of the tube from stray X-radiation, primary or secondary electrons from inside the control electrode assembly.

A slightly different embodiment of our invention is shown in Figure 4. Here the anode arm

12 and the cathode arm 13 are in line, the radiation opening in the control electrode being directed toward a side wall of the envelope, and the anode rod being provided with a right angle bend 47 to place the coned target surface in the proper position. The relationship of the anode, cathode and control electrode is the same as in the previously described tube.

Figures 5, 6, and 7 represent diagrammatically and reduced to lowest terms various circuits in which our tube may be used, each of the drawings showing the anode tip in different degrees of insertion.

In Figure 5, the cathode 32 is energized by a source 49, the anode being usually energized from an alternator 50 either directly whereby the tube becomes self-rectifying, or preferably through a rectifier, as is well known in the art. The control electrode is maintained at a potential different from that of the cathode by a biasing source 51 or in some cases by a resistor 52 which will then cause the control electrode to become negative due to accumulation of electrons during operation. In some cases it may be desirable to let the control electrode float free without connection, in which case it will charge up to a high negative potential, but will not usually block the anode current at the anode potentials in vogue, as there is always some slight leakage in the supports.

In operation the annular cathode emits an annular cloud of electrons, some of which are drawn through the annular aperture to the coned target surface and others are returned to the cathode, a discoidal stream of electrons being formed which is dense near the cathode and thinning out toward the anode. This cloud of electrons constitutes the space charge, and its formation is encouraged by the enclosure of the cathode. Varying potentials placed on the control electrode will control the amount of current reaching the anode; in general, a negative potential decreasing the current, and a less negative potential increasing it.

Due to the shape of the annular aperture however, placing a potential on the control electrode will also change the dimensions or shape of the stream. The equipotential lines produced when the control electrode is energized are indicated by the numeral 54 and the general path of the stream section by the dotted line 55. Increasing the negative potential on the control electrode will make the stream thinner, and decreasing the negative potential will thicken it. Thus the thickness of the stream can be controlled, the end result being the same as if the physical annular aperture 27 were to be changed in dimension. We have therefore given the name of electrical aperture to the condition existing in the annular aperture when energized.

Several results apart from the gross control of current may be accomplished by the use of the electrical aperture. By changing the thickness of the stream a greater or less amount of target surface may be bombarded, thus changing the size of the focal spot, for various types of radiography. The shape of the spot will be determined by the position of the coned target surface. If placed so that the apex of the cone passes completely through the stream, the spot will be a ring which may be made narrow or wide. If the cone is retracted as in Figure 5, the entire emission can be concentrated on the very tip, or allowed to include a coned surface

of varying size, all of which adds to the versatility of the device.

In case the tip is withdrawn along the axis of the circle away from the center as in Figure 5, the discoidal stream will become slightly dished in the central portion only, as the equipotential lines hold the stream in shape until the electrons pass out of the electrical aperture, thereafter turning toward the tip. As the electrons are rapidly increasing their velocity, they drive close to the center of the circle before turning to bombard the anode tip. In other positions where the tip is close to the center, practically no dishing occurs.

In Figure 6 a circuit is shown, as in Figure 5 except that the upper and lower portions of the control electrode are electrically distinct and a separate biasing source 56 is shown for the upper portion. By adjustment of potentials, both the direction and amount of the stream may be controlled to produce conditions only obtainable in the previously described tube by physically withdrawing or inserting the anode tip into the stream, a construction which is not easily feasible in a single tube.

Figure 7 represents a circuit in which the tube as above described will oscillate. The circuit is the well known tuned grid tuned plate circuit, a control resonant circuit 57 being placed in series with the control bias, and an anode resonant circuit 59 in series between the anode and cathode. A blocking condenser 60 is preferably placed between the anode and the resonant circuit and the high voltage parallel fed from the usual transformer 61 through the rectifier.

We have found that the tube as described can be set into self-oscillation at a frequency of 7,500 kilocycles without difficulty and when it is oscillating the high frequency pulsating X-ray beam appears to have a penetration quality somewhat different than that to be expected from the actual applied voltage. Such penetration has been experimentally observed and therapeutically used, but we are not at this time ready to express an opinion as to the reason therefor.

However, as the frequency of oscillation is determined by the tuning of the control electrode circuit, the reaction of the anode circuit being inductive, variation of the tuning of the anode resonant circuit will change the relative phase of the anode potential and anode current, without substantially changing the oscillation frequency. This change in phase relation gives rise to internal conditions differing widely from those in the ordinary X-ray tube, and may well modify the resultant beam to an extent such as to produce the results experimentally demonstrated.

It should also be noted that the self-oscillation of the X-ray tube gives rise to an entirely different set of internal conditions than those produced by supplying the anode from a high frequency source as has been done in the prior art. In the self-oscillatory tube here described the control electrode is also involved and the resultant phase relations produce a pulsating X-ray beam having entirely different characteristics than that produced by an ordinary tube having the anode energized by high frequency alternating current.

The X-radiation of the device however, does have a homogeneity, to which we believe there is a reasonable explanation. It is well known that the X-rays from a tube consist of two main classes; the heterogeneous spectrum of general

radiation within a range of quality which depends solely on the speeds of the parent electron streams; and the homogeneous or monochromatic radiations which are characteristic of the target metal. At high voltages the bulk of the radiation is of the latter type, but in tubes using unfiltered alternating current, there is a large component of the softer heterogeneous rays generated as the anode voltage rises to the point where the homogeneous radiations begin, the relative amounts depending on the wave form applied to the anode.

By creating a space charge, and by using a strong negative potential on the control electrode, we are able to prevent anode current from flowing during the low voltage portions of the wave at the beginning and end of each half cycle, and thus greatly reduce the amount of the so-called general radiation, leaving the bulk of the X-ray beam hard rays of the homogeneous type. The effectiveness of the tube and the therapeutic efficiency is thus greatly improved.

It should be observed that high negative potentials may be used on the control electrode without changing the quality or hardness of the X-radiation from the anode. The net potential difference between the anode and cathode is the dominating factor, controlling as it does, the speed of the electrons bombarding the anode. The velocity of the electron stream will be held down by the potential of the control electrode while the electrons are within the limits of its influence, but after they escape through the electrical aperture and pass toward the anode, they are accelerated again at a rate which will land them against the anode with not less than the same velocity as they would have if they had started from the cathode and proceeded to the anode without influence of any control electrode or control potential.

There is also experimental evidence to indicate that the quality or hardness of the final X-ray is such that greater penetration for a given anode-cathode potential difference is obtained from our tube with the cathode emission controlled by the electrical aperture of our invention. While we realize that the quality or hardness is customarily said in textbooks to be entirely determined by the anode potential, we have obtained reliable experimental evidence of greater effective penetration in the rays emitted from the tube as described, although we do not at this time care to offer an explanation of that discovery.

Several further features of our invention should be pointed out. The cathode and focal spot being enclosed, and the walls of the control electrode being of sufficient thickness to stop casual X-rays, practically no X-radiation passes out except through the radiation aperture. The cover 21 of the control electrode, although it may be somewhat thinner than the rest of the control electrode, prevents X-radiation along the back of the tube, and as the diameter of the anode rod is larger than the aperture in the cover, complete shielding is provided. Furthermore, the enclosed construction prevents stray electrons from striking the glass to form hot spots and eventual puncture. The construction as shown therefore, completely shields the envelope from both the cathode rays, and the X-rays except through the proper path, and no auxiliary internal or external shields are necessary for the protection of the operators from stray radiation.

It is also possible to regulate the anode current to provide a uniform output even though slight

irregularities in line voltage may occur. In ordinary tubes operating at saturation without space charge or control, such variations in line voltage change the cathode temperature with resultant fluctuations of milliamperage, and much elaborate compensating equipment.

We claim:

1. The method of generating X-rays which comprises the steps of forming an annular cloud 10 of electrons, directing said electrons inwardly to a common center, intersecting said cloud adjacent said center to produce a stream of X-rays directed outwardly along a line perpendicular to the plane of the electron path, and varying the 15 thickness of the electron stream to vary the diameter of the X-ray stream.

2. The method of controlling the X-ray beam emitted circumferentially from a conical anode,

which comprises forming an annular cloud of electrons concentric with the axis of said anode, directing said electrons inwardly to bombard the cone of said anode, and varying the thickness of the electron stream to define the amount of anode 5 surface bombarded by said electrons.

3. The method of generating X-rays which comprises the steps of forming an annular cloud of electrons, directing said electrons inwardly to a common center, intersecting said cloud adjacent 10 said center to produce a stream of X-rays directed outwardly along a line perpendicular to the plane of the electron path, and varying the thickness of the electron stream to control the X-rays produced.
